(57) **CLAIM**

The ornamental design for a headstone flower holder, as shown and described.

DESCRIPTION

FIG. 1 is an environmental perspective view of a headstone flower holder showing my new design;

FIG. 2 is a front elevational view thereof;

FIG. 3 is a rear elevational view thereof;

FIG. 4 is a top plan view thereof; and,

FIG. 5 is a right side elevational view with the left side being a mirror image thereof.

The broken line showing of the flowers and the headstone in FIG. 1 is for illustrative purposes only and forms no part of the claimed design.
